UNITED STATES PATENT OFFICE.

TIMOTHY D. FREDERICK, OF SAN FRANCISCO, CALIFORNIA.

DESIGN FOR A RULE-HOLDER.

57,831.

Specification for Design.

Patented May 10, 1921.

Application filed December 2, 1920. Serial No. 427,917. Term of patent 7 years.

To all whom it may concern:

Be it known that I, TIMOTHY D. FREDERICK, a citizen of the United States, residing at San Francisco, in the county of San Francisco and State of California, have invented a new, original, and ornamental Design for a Rule-Holder, of which the following is a specification, reference being had to the accompanying drawing, forming part thereof.

The figure is a perspective view of a rule holder, showing my new design.

I claim:

The ornamental design for a rule holder, as shown.

TIMOTHY D. FREDERICK.
